UNITED STATES PATENT OFFICE

2,384,246

UNDERGROUND CONDUIT

Frazer W. Gay, Metuchen, N. J.

Application September 1, 1942, Serial No. 456,909

9 Claims. (Cl. 61—45)

This invention relates to an underground conduit adapted to carry fluid under high pressure. Pursuant to this invention it is proposed to bore out said conduit in earth or rock and to shape the conduit with flat sides with the structure so arranged that cracks will tend to open only at corners where means are provided to seal said cracks to prevent excessive leakage.

A conduit according to this invention can readily be adapted to carry the fluid piston in a Diesel pump such as described in my United States Patent No. 1,846,389, dated February 23, 1932, or in my United States patent application Ser. No. 483,363, filed April 16, 1943.

Pressures upon a conduit surface may vary from a relatively great value at the inner or working end to a relatively low value at the outer end.

At the inner or high pressure end of the conduit, I propose to make concrete cylinder walls thick, so that the relatively small internal surface of the conduit is adapted to support a relatively great per unit fluid pressure, and the thick wall will transmit this pressure to a relatively great area of earth (n times the area of an internal wall surface, n meaning any given or selected number of times) which supports the pressures at a much lower per unit value ($1/n$). As the maximum per unit pressure decreases along the conduit, progressing from the working end outwards, and as the depth increases with corresponding increase in the normal per unit rock pressure, the thickness of concrete quickly becomes a minimum and the per unit pressure on the rock is substantially the same as the per unit pressure on the inside of the conduit.

According to the instant invention, all pneumatic and hydraulic conduits, wherever subjected to pressures materially greater than the adjacent earth pressures, are constructed to provide a plurality of angularly related plane surfaces, and means are provided to seal cracks between such plane surfaces against leakage therethrough of fluid contained within the conduit.

It is well known, if cylindrical conduits formed in rock are used to carry fluid at a pressure much greater than the pressure prevailing in the rock due to its overburden, that cracks will develop in the passage or conduit walls, by reason of the compression of the earth material adjacent to the conduit passage, and consequently the cylindrical bore becomes enlarged and the rock structure, although in compression radially, is put under tension circumferentially. Fluid contained in the conduit under high pressure will enter said cracks and compress the rock circumferentially each

side of a crack, so that the high pressure fluid acts as a wedge which tends to continuously drive deeper and deeper into the crack, and consequently leakage tends to progressively increase.

According to the instant invention I propose to open up cracks where flat or plane surfaces of the conduit intersect, and, since the pressure on any flat surface is everywhere parallel and perpendicular to the plane thereof, the rock adjacent each flat surface will only be under compression, and there will be no tendency to development of cracks in such surfaces. However, since the pressures on adjacent angularly related flat surfaces will act to widen any crack intentionally produced where said flat surfaces meet or intersect, these cracks are sealed to prevent fluid leakage.

I propose to effectively drain to the surface of the earth all cracks intentionally produced between adjacent angularly related flat surfaces by connecting said cracks by a plurality of ducts increasing in size as they approach the surface of the earth, whereby any liquid or gas leaking past the seals into the cracks, and between opposed surfaces of the latter, loses most of its pressure, and consequently there is substantially no increase in the adjacent earth pressure caused by leaking fluid. In constructions where the conduit is carrying liquid only, the sealing means comprises merely a plurality of rods shaped to fit the inside of the conduit conformably to adjacent angularly related flat surfaces thereof, and so as to fit closely against and close the intermediate crack, said rods being dovetailed into each other or keyed together in order to permit some longitudinal movement between sections thereof without leakage where thus joined. Means are provided for holding the rods in position, and pressed securely throughout their entire length against the crack to be sealed.

Portions of the high pressure end of the main conduit which contain gases are sealed off at the fabricated drainage cracks by interposing between the interior thereof and said cracks small hydraulic seal conduits which are split into two halves. One half of such seal conduit is secured to one of the angularly related flat main conduit surfaces bordering a crack and the other half thereof is secured to the other of said flat surfaces, in such manner that the split on one side of a seal conduit constitutes a crack between said angularly related flat surfaces, and the split on the other side of said seal conduit opens into or communicates with the external fabricated drainage crack. These small hydraulic seal conduits, which are applied at all

main drainage cracks in a large conduit carrying gas, is everywhere subjected to an internal hydraulic pressure considerably exceeding the gas pressure existing anywhere within said large conduit or portion thereof carrying a body of gas. The two splits in the high pressure hydraulic seal conduits are sealed in the same manner as are the drainage cracks leading from the portions of the main conduit adapted to carry liquid. There will be a small leakage along the splits of the seal conduits on one side into the main or gas filled conduit and on the other side into the outgoing fabricated earth crack, but at no point will it be possible for the high pressure gas contained in the main conduit to escape into and through the thus sealed drainage crack.

It is an object of this invention to form underground ducts or conduits bounded by a plurality of plane flat surfaces angularly related, whereby all internal pressures are parallel and perpendicular to said surfaces, and there is no tendency for any such surface per se to develop cracks.

It is a further object to fabricate or leave cracks where adjacent angularly related conduit surfaces join and to seal said cracks against leakage from said conduit interior, whereby the amount of liquid leaking through said fabricated cracks is held to a minimum value.

It is a further object of the present invention to drain said fabricated cracks to the surface of the earth, whereby the pressure developed by fluids leaking through said cracks can never greatly exceed the head of water existing above said cracks up to the surface of the earth above.

It is a further object to support the sealing means comprising rods, or other sealing devices along and in closed relation to said fabricated cracks, and to provide means whereby said sealing means is securely pressed against said cracks.

It is a further object of the present invention to provide a hydraulic seal at said fabricated cracks at points where the main conduit is designed to support gas pressure; said seal comprising a relatively small auxiliary or seal conduit running along and opposed to the mouth of the crack between adjacent angularly related plane surfaces of said main conduit. The crack between said plane surfaces including the crack in between parts of said relatively small auxiliary seal conduit. Hydraulic pressure is maintained at all times in said relatively small seal conduit having a value greater than the corresponding pneumatic pressure in said gas carrying part of the main conduit, whereby sealing liquid will always leak from said small auxiliary seal conduit into said main conduit; and gas from said main conduit may never leak out against the higher hydraulic pressure into said auxiliary seal conduit. Where pressures are low and main conduit surfaces are small, only one crack may be required in said small auxiliary seal conduit; but where the flat surfaces of the main conduit are large, or pressures in said main conduit are great, the external fabricated crack may be expected to open up to such an extent that the material of the small seal conduit would be strained. In such cases, it is an object of this invention to place two slits in said small seal conduit, one to communicate with the main conduit interior, and the other to open into the exterior fabricated drainage crack.

It is a further object of this invention to provide an auxiliary sealing duct means in extension

along an earth crack leading outwardly from a gas carrying underground conduit, said sealing duct being formed to provide crack-like communication between its interior and the conduit interior and opposite crack-like communication between its interior and said earth crack, and to maintain a hydraulic seal and pressure in said sealing duct means at every point and at any instant greater than gas pressure in said main conduit at said instant and at said point, whereby leakage is always from said sealing duct means into said main conduit and said leakage is held to a minimum value.

Other objects of this invention not at this time 15 more particularly enumerated will be clearly understood from the following description of same. The invention is clearly illustrated in the accompanying drawings, in which—

Fig. 1 is a sectional view of an underground 20 conduit constructed according to this invention.

Fig. 2 is a plan view showing the structure between the high pressure end of the conduit and the surrounding rock.

Fig. 3 is an enlarged vertical cross-sectional 25 view, taken on line C—C in Fig. 1.

Fig. 4 is a further enlarged sectional view of one of the sealing means shown in Fig. 3.

Fig. 5 is an enlarged longitudinal cross sectional view of adjoined seal blocks shown in 30 Fig. 3.

Fig. 6 is a cross sectional view of a sealing means between angularly related flat surfaces of the high pressure end of the conduit.

Fig. 7 is a cross sectional view of a gas seal 35 means for use at a closed extremity of the high pressure end of the conduit.

Fig. 8 is a cross sectional view of an expansion joint and seal between longitudinal sections of the main conduit lining skin.

Fig. 9 is a diagrammatic illustration of means 40 for maintaining hydraulic pressure in the seals of Figs. 6 and 7.

Similar characters of reference are employed in the above described views to indicate corresponding parts.

Referring to the drawings, Fig. 1 shows the application of a conduit embodying the principles of the present invention to a Humphrey pump. The working or pump end section 13 of the conduit is enlarged and is that portion thereof which is subject to the greatest fluid pressure. This end of the conduit is furthermore nearest to the surface of the earth where the natural rock pressure due to overburden diminishes rapidly to zero 55 at the surface.

From the end 29 of the conduit 13, 21, 22 pressure within the same decreases rapidly as progress is made toward the end at 23 where pressures are never greatly above the static head of water at that point. Furthermore the natural pressure in the rock increases with depth whereby the highly compressed rock is quickly able to withstand the greatly reduced pressure as the play pipe section 22 of the conduit is approached.

Figure 2 shows the method employed for spreading the high pressure integrated against the surfaces 15, 15, 15, 15 of the conduit end section 13, so that these great pressures at the weak rock 70 surface are spread over the relatively great surfaces 31, 31, etc., and are taken up by the thick backing of the continuous wall on the side adjacent conduit extension 21. The weak earth structure under low natural pressure adjacent the surface of the earth is enabled to carry the highly

concentrated pressures within conduit end action 13 by causing the loads to be borne by the massive concrete walls around said conduit end, and the massive structure which spreads these concentrated loads over a rock structure of great area, n times the area of the conduit wall, even though this rock is of relatively low per unit strength. Figure 1 shows that, progressing away from end 28, the massive rock spreader structure is reduced in volume as progress is made into the earth where the natural pressure in the rock quickly approaches the rapidly decreasing pressure in the conduit 13, 21, 22. Cracks 38, 38, 38, 38, see Fig. 2, are of course extended to the rock structure 31, 31, 31 and enlarge toward the surface to give ample area for the escape of fluid that may leak out of conduit end section 13 so that there is no possibility of fluid pressure building up in the rock structure 31, 31, 31.

The high-pressure exit chamber opens out through the arched opening 28 into the conical guide reducer 21. Liquid flows from the guide reducer 21 into and through the rectangular play pipe section 22 of the conduit. A cross-sectional view of this play section 22 of the conduit is shown in Fig. 3, said section being taken along line C—C in Fig. 1. While the drawings show a rectangular play pipe section 22, it is to be understood that the same may be of any other polygonal shape in cross-section. The low pressure end of said play pipe section 22 expands outwardly through the expanding elbow 23.

It will be noted that the entire force on the walls of the working or pump end section 13, on the walls of the reducer 21, and on the walls of the play pipe section 22, is taken by the rock structure of the earth, leaving only the upward force at the end 29 of the working or pump end section 13 to be otherwise carried. As shown, the upward force is carried by a weighty head or stopper 16 comprising an enormous mass of concrete and gravel. The main structure of this stopper is reenforced concrete, but a great part of the weight thereof is made up by a filling which is preferably rock and gravel.

The main play pipe section 22 is formed by a plurality of flat walls 70, 70, etc.; and at each corner where these flat walls meet there is left a crack opening into a crevice 12, 72, etc. cut out of the rock and forming an outgoing passage. The pressure within the play pipe section 22 will cause the cracks to extend as at 81, at locations where the pressure is sufficiently high. These passages 72, 72, etc., are drained by the drain pipes 73, 73, etc., so that it is not possible for hydraulic fluid leaking out of the play pipe section 22 to build up high pressures outside of the conduit itself. It is to be understood that this section 22 of the conduit, and other similar structures, are lined by a thin steel skin 124; and in the preferred form of the lining, I elect to place small passages at frequent intervals between the lining skin and the concrete which drain into the drain passages 72, 72, etc., so that leakage (if any) will break out into the passages 72 and will not build up destructive pressures in any part of the rock structure. Fig. 3 shows the cracks sealed by the sealing blocks 14, 74, etc., and it further shows the sealing blocks protected against fluid friction by the thin anti-friction baffles 71, 71, etc., so that the interior of the hydraulic conduit section 22 exposes at all points only flat or slightly curved surfaces to the flow of the water. It will be noted that the baffles 71 provide a small auxiliary duct

in each corner. It is proposed to block this duct at frequent intervals so that hydraulic fluid will not flow in these small ducts, the flow being confined entirely to the central passage. Frequent small openings will be provided through the baffles 71 so that the pressure on both sides of the baffles will be substantially equal.

Fig. 4 shows an enlarged section included in the ring R of Fig. 3. Fig. 4 shows one sealing block 14 in the corner formed by two Z-bars 75, 75. These Z-bars each have one of their flanges forming part of the wall of the drain passage 72. The other flange of the Z-bar is within the cylinder and at frequent intervals has holes drilled in it to accommodate the pipes 76, 76, which are welded in place and form guides for the springs 78, 78. These springs each press a seal block 14 securely into the corner of the conduit section 22 without regard to the pressure within the latter. Fig. 4 also shows the longitudinal stops 86, 86. These stops engage lugs on the seal block 14 (not shown) which allow the seal blocks 14 to move a very limited amount longitudinally.

Fig. 5 shows an enlarged cross section of the sealing key 80 of Fig. 4, as enclosed by the ring marked N in Fig. 4. 82, 82 are keyways carefully cut in the ends of seal blocks 14, 14 so as to exactly match. The key 80 is made to fit in the keyways very closely, and longitudinal stops 83, 83 are welded into the keyways to allow the key 80 only a limited longitudinal motion. This key 80 seals the hydraulic fluid which would otherwise escape out of the conduit through the crack 84 between adjacent sealing blocks 14, 14 and thence directly through the crack at this point between the flat walls of conduit section 22.

Fig. 6 shows two flat walls 15, 15 of the working or pump end section 13 of the conduit and a gas seal to prevent gases within the section 13 from leaking through the cracks where the flat surfaces 15, 15 join. This seal comprises a small passage 90, one corner of which comprises one of the cracks between walls 15, 15 in the interior of the conduit section 13. Diagonally opposite this crack is another crack which communicates with the drain passage 72. The hydraulic pressure in the small passage 90 is maintained always greater than the gas pressure in the conduit section 13 so that the liquid in the passage 90 will always leak outwards either into said conduit section 13 or into the drain passage 72. Seals 74, 74 reduce the flow of liquid out of the passage 90 in the same manner as the seals 14, 14 in the passage of conduit section 22, as shown in Fig. 4.

The metal structures 93, 94 and 95 constitute the walls of the small passage 90 and are arranged to provide access to the seal blocks 14, 14 as shown. It will be understood that it is necessary to make provisions in the head or stopper 16 as shown in Fig. 1, so that these corners are accessible. This will of course slightly increase the clearance in the conduit section 13, and the amount of this objectionable clearance will be kept to a minimum by filling the corner openings with bolted-in blocks.

Fig. 7 shows a gas seal around the top of conduit section 13 between the rock structure 31 and the head or stopper 16. This is very similar to the construction shown in Fig. 6. In this case the high-pressure passage 100 vents on the outside where leakage must be drained and pumped away, and on the inside into the conduit section 13.

Fig. 8 shows an expansion joint, as for instance

as at P and Q, in the conduit section 22 (Fig. 1 and Fig. 2). Steel blocks 122, 122 are welded to the skin 124 of the conduit section 22, and the small crack p between these steel blocks is vented to the drain 35. Other small drains as 39, 39, 39 are shown so as to maintain a relatively low pressure back of the steel skin 124, 124 which is secured to the outer concrete walls 70, 70 by the welded-on tacks 123, 123, etc. The flap 36 is mortised into the corner seal blocks as shown diagrammatically at 38, 38 in Fig. 4. The seal flaps 36 are pressed down by steel springs 37 held in position by steel blocks 38. Steel blocks 38 are welded to the skin 124.

Fig. 9 shows one way to maintain the necessary excess pressure in the gas seals, as for instance in the seal duct 90 shown in Fig. 6 for the vertical cracks, and in the seal duct 100 shown in Fig. 7 for horizontal cracks. In Fig. 9, 108 represents a motor driving a centrifugal pump 107. This centrifugal pump takes fluid from the fluid piston at the bottom of the conduit section 13 through the pipe 97, increases its pressure, and discharges it into the pipe 98. This fluid which is maintained at a pressure of approximately 100 lbs. above the liquid pressure in conduit section 13 is led by pipes 190, 190, etc., into the vertical seal passages 90, 90, etc., and by pipes 109, 109, etc., into the horizontal seal passages 100, 100, etc.

Many changes could be made in the above construction, and many apparently widely different embodiments of this invention could be made without departing from the scope thereof. It is intended that all matter pertaining to the above description, or shown in the accompanying drawings, be interpreted as illustrative and not in the limiting sense.

What is claimed is:

1. In a conduit in the earth adapted to carry fluid at relatively high pressure comprising: a portion of said conduit having a plurality of flat sides, a mechanically strong structure built between each said flat side and the earth and having a relatively greater surface area at its outer earth contacting face, said structure supporting the fluid pressure in said conduit portion acting on the relatively small surface of said conduit flat sides at relatively high unit pressure and transmitting said pressure to a relatively large earth surface at relatively low unit pressure, and a drained crack along the intersecting edges of adjacent conduit flat sides of said conduit portion, whereby leakage from said high pressure fluid is drained away at relatively low pressure, and seals along said cracks to reduce fluid leakage from said conduit.

2. In a conduit in the earth adapted to carry fluid at relatively high unit pressure comprising: a portion of said conduit having a plurality of flat sides, a mechanically strong structure built between each said flat side and the earth and having a relatively greater surface area at its outer earth contacting face, said structure supporting the fluid pressure in said conduit portion acting on the relatively small surface of said conduit flat sides at relatively high unit pressure and transmitting said pressure to a relatively large earth surface at relatively low unit pressure, a drained crack along the intersecting edges of adjacent conduit flat sides, whereby leakage from said high pressure conduit is drained away at relatively low pressure.

3. A conduit in the earth adapted to carry gas at high pressure; said conduit comprising: flat sidewalls supported by said earth and intersect-

ing at angles, cracks at said angles, and small ducts arranged along each said crack, each said small duct also having longitudinal cracks and the crack where two sides of said large gas-handling conduit intersect also being the crack in the associated small liquid-carrying duct and pressure producing means connected to continually maintain a liquid pressure in said small ducts higher than said gas pressure in said conduit.

4. A conduit in the earth adapted to carry gas at high pressure; said conduit comprising: flat sidewalls intersecting at angles, cracks at said angles and small ducts arranged along each said

crack, each said small duct also having longitudinal cracks, and the crack where two sides of said large gas-handling conduit intersect also being the crack in the associated small liquid-carrying duct and pressure producing means connected to feed liquid to said small liquid-carrying duct whereby the contained liquid is always maintained at a pressure higher than said gas pressure in said conduit, and means to seal the cracks in said liquid-carrying ducts.

5. In a conduit in the earth adapted to carry fluid at high pressure, a portion of said conduit having flat side walls supported by said earth and intersecting at angles so as to provide intervening cracks, drains through the earth along said cracks to drain off leakage emitted through said cracks, said drains being of substantial cross-sectional area so as to maintain the pressure in said drains at a relatively low value, blocks snugly fitted within the side wall angles adapted to seal said cracks, and means to maintain said blocks firmly thrust into said angles.

6. In a conduit in the earth adapted to transmit fluid at high pressure, a portion of said conduit having flat metallic side walls, concrete masses interposed between said side walls and the surrounding earth, said side walls and concrete masses intersecting at angles so as to provide intervening cracks, duct means exteriorly of said conduit contiguous to said cracks adapted to receive and carry off leakage emitted through said cracks, means to drain said duct means whereby to prevent pressure build up therein of said emitted leakage, and hydraulic seals snugly fitted within the angles of said side walls to hold leakage through said cracks to a minimum.

7. A conduit in the earth adapted to transmit fluid at high pressure comprising a plurality of angularly adjoined flat side walls, each side wall comprising a metallic inner face liner having reinforced edge portions, a supporting concrete wall body between said liner and the adjacent earth mass, whereby to rigidly back each side wall by said earth mass, juxtaposed reinforced edge portions of adjoining liners being arranged to provide intervening cracks, said earth mass having drain means formed therein for communication with said cracks, whereby to receive fluid leaking outwardly therethrough from said conduit, said drain means including fluid venting means, whereby to prevent exertion of excessive fluid pressure within the earth mass, and hydraulic seal means snugly thrust into the interior angles of adjoining liners, whereby to reduce leakage from the relatively high pressure conduit into said relatively low pressure drain means.

8. A conduit in the earth adapted to carry fluid at high pressure comprising a plurality of angularly adjoined but independent side walls adapted to provide narrow cracks intermediate contiguous margins thereof, each side wall comprising an

inner metallic liner member having reenforced side margins and a concrete outer member backed by said earth whereby to provide unyielding support for said liner member, means exteriorly of the conduit adapted to receive and freely drain off fluid leakage emitted through said cracks from the conduit interior, and hydraulic seal means snugly thrust into the interior angles of adjoining liner members, whereby to reduce leakage from the conduit interior through said cracks.

9. A conduit in the earth adapted to carry fluid at high pressure comprising a plurality of flat walls supported by the surrounding earth, said surrounding earth having cracks along and in-

5 termediate opposed edges of adjoining walls and extending radially outward along lines of maximum earth stress, whereby the fluid pressure within the conduit acting normal to all said flat walls tends to open said cracks only by pressure exerted within the included angle of adjacent walls, so that said cracks may open and close with changes in pressure or temperature, a rigid, mechanically strong and impermeable lining for each 10 said wall, drains cooperative with said cracks, and hydraulic seals cooperative with the wall joints adapted to reduce leakage therethrough to a minimum.

FRAZER W. GAY.
